UNITED STATES PATENT OFFICE.

WILLIAM Q. TOLMAN, OF NEW BEDFORD, MASSACHUSETTS, ASSIGNOR TO
THE PAIRPOINT MANUFACTURING COMPANY, OF SAME PLACE.

DESIGN FOR A BOX-COVER.

SPECIFICATION forming part of Design No. 22,725, dated August 22, 1893.

Application filed March 31, 1893. Serial No. 468,615. Term of patent 7 years.

To all whom it may concern:

Be it known that I, WILLIAM Q. TOLMAN, a citizen of the United States, residing at New Bedford, in the county of Bristol and State of Massachusetts, have invented and produced a new and original Design for a Pattern for Box-Covers, &c., of which the following is a specification, reference being had to the accompanying drawing, showing a cover provided with my new pattern.

The leading feature of my design consists in the combination of scrolls arranged in such relation to each other as to inclose a space of some greater length than width, adapted to

receive any desired inscriptions, whether plain or ornamental; α is a plate and α' and α'' reversed scrolls, which with the scroll α^3 form approximately the four sides of the parallelogrammatic space b adapted to receive the inscription if desired, as already indicated.
